UNITED STATES PATENT OFFICE.

HORACE BEARD, OF WILTON, NEW HAMPSHIRE.

ANTI-RATTLER FOR THILL-COUPINGS.

SPECIFICATION forming part of Letters Patent No. 247,875, dated October 4, 1881.

Application filed August 27, 1881. (No model.)

To all whom it may concern:

- Be it known that I, HORACE BEARD, of Wilton, of the county of Hillsborough and State of New Hampshire, have invented a new and useful Improvement in Anti-Rattling Devices for Thill-Couplings; and I do hereby declare the same to be described in the following specification and represented in the accompanying drawings, of which—
- 10 Figure 1 is a top view, Fig. 2 a side elevation, and Fig. 3 a longitudinal section, of a thill-coupling with my improved anti-rattling spring or device adapted thereto. Fig. 4 is a view of the spring as it appears on being formed or struck from a metallic plate and previous to it being bent in manner as shown in Fig. 5, which is an edge view of the spring as it appears when ready for application to a coupling.
- 20 The object of my invention is to make a spring that cannot be "set" or broken by raising and turning backward the thill, and that can be inserted without uncoupling the thill or removing any part of the vehicle.
- 25 In carrying out my invention I construct the spring or anti-rattling device with an opening or passage extending from front to back through the portion of it that projects above the joint of the coupling, such opening or passage being of a size that will admit of the thill being turned upward and backward against

the clip without contact with or doing injury to the spring.

In the drawings, A denotes the thill, and B the clip, with which it is coupled in the usual manner, as represented. The anti-rattling spring (shown at C) is formed of a strip or piece of plate metal, and is shaped essentially as exhibited in Fig. 4, it being an ellipse, having an elliptic opening, c, through it, and also having projections *b b* extending from it at the ends of its longer axis. On the plate being bent as shown in Fig. 5, and compressed and applied to the coupling in manner as represented in Fig. 3, such plate becomes by its inherent elasticity a spring to prevent rattling of the coupling. On the thill being turned upward it cannot be forced in contact with the spring to do injury thereto, as the thill will be received within the opening and not touch the spring.

What I claim as my invention is—

The described improved anti-rattling device or spring, as made with the opening or passage *c* extending through it from front to back, in the part of it which, when it is applied to a thill-coupling, is to project above the joint thereof, all being substantially as set forth.

HORACE BEARD.
